BOBBIN CHUTE FOR WEFT REPLENISHING LOOMS

Filed Oct. 10, 1940

FIG. 1

UNITED STATES PATENT OFFICE

2,263,257

BOBBIN CHUTE FOR WEFT REPLENISHING LOOMS

William A. Blanchard, Millbury, Mass., assignor to Crompton & Knowles Loom Works, Worcester, Mass., a corporation of Massachusetts

Application October 10, 1940, Serial No. 360,615

13 Claims. (Cl. 139—255)

This invention relates to bobbin chutes for weft replenishing looms and it is the general object of the invention to provide a chute which can be readily fitted to the customary form of multiple cell shuttle boxes.

The ordinary gang of shuttle boxes has a vertical pin on which are pivoted the shuttle binders which check the shuttles as they enter the boxes. It is an important feature of my present invention to construct a chute one end of which will be held in position by the binder pin.

The gang of shuttle boxes is generally constructed with a front plate or wall located at that end of the boxes adjacent to the cloth being woven. It is a further object of my present invention to provide a bobbin chute constructed to have portions thereof which will slide into holding engagement with the front wall, the latter together with the binder pin holding the bobbin chute in position.

The shuttle binders are ordinarily mounted between lugs which project forwardly from the gang of boxes. One set of lugs located at the outer end of the shuttle boxes receives the binder pin while the other set of lugs near the inner end of the boxes serves as guides for the free ends of the binders. It is a further object of my present invention to provide the bobbin chute with retaining portions which fit between adjacent lugs, the latter thereby preventing substantial vertical motion of the chute with respect to the gang of boxes.

It is another object of my present invention to construct a bobbin chute of sheet material possessing sufficient inherent resilience so that the rear part of the chute will be held against a back wall of one of the shuttle boxes by reason of the resilience of the chute. By this construction the bobbin chute is prevented from vibrating during the back and forth swing of the lay which carries the shuttle boxes.

With these and other objects in view which will appear as the description proceeds, my invention resides in the combination and arrangements of parts hereinafter described and set forth.

In the accompanying drawing, wherein a convenient embodiment of my invention is set forth:

Fig. 1 is a front elevation of one end of a loom lay showing the gang of shuttle boxes with my invention applied thereto.

Fig. 2 is a vertical section on line 2—2 of Fig. 1 looking toward the outer end of the lay and showing the bobbin chute in position for delivering the depleted bobbin to the right.

Fig. 3 is a detailed horizontal section on line 3—3 of Fig. 1 on an enlarged scale.

Fig. 4 is a detailed vertical section on line 4—4 of Fig. 1 looking toward the center of the loom.

Fig. 5 is a horizontal section on line 5—5 of Fig. 1 on an enlarged scale, and

Fig. 6 is a horizontal section on line 6—6 of Fig. 1 on a reduced scale.

Referring particularly to Fig. 1, I have shown the loom lay L and one of the swords 10 on which it is mounted. Projecting to the right from the sword is a lay end 11 having an inner guide plate 12 which is grooved as at 13 to receive a tongue 14 on the inner end of a gang of shuttle boxes G. An outer guide plate 15 similar to the plate 12 is provided with a guide groove 16 to receive a tongue 17 on the outer or right hand end of the gang of shuttle boxes as viewed in Fig. 1.

In the present instance the gang G is formed with four different shuttle receiving cells represented respectively from top to bottom at 20, 21, 22 and 23. The cell 20 is provided with a horizontal top plate 25, while the lower cell 23 is provided with a bottom plate 26, and intermediate plates 27 form the floors of the three upper cells. A box lifter rod 30 is secured to the bottom plate 25 and is reciprocated vertically to place any one of the cells in active picking position with respect to the race plate 31 of the lay. During vertical reciprocation of the boxes the tongues 14 and 17 slide in the grooves 13 and 16, respectively.

As shown in Fig. 6 the shuttle boxes are provided at their inner ends with front vertical wall or plate 35 from which project a series of vertically spaced lugs 36. The outer end of the gang is provided with another plate 38 also provided with vertically spaced lugs 39. A shuttle binder pin 40 passes vertically through the lugs 39 and serves as a pivot for binders 41. In Fig. 1 I have shown two binders but it is to be understood that when the boxes are to be used for non-automatic pick and pick weaving there will be a binder for each of the shuttle cells. As shown in Fig. 1 the boxes are arranged for automatic weaving and the binders have been removed from the lower cells 22 and 23. The binder pin 40 however extends entirely through all of the lugs 39. Forward motion of the inner or free ends of the binders shown at the left in Fig. 1 is restrained by a stop pin 42 extending vertically through the lugs 36.

At the top of Fig. 1 I have shown a transfer arm 45 forming part of a weft replenishing mechanism for the purpose of replenishing the shuttle S in the top cell 20. It is thought sufficient for purposes of the present description to

state that at the time of a weft replenishing operation of the loom the transferred arm 45 will descend to place a fresh reserve bobbin R shown in Fig. 2 into the shuttle S and at the same time push the empty or depleted bobbin D out of the shuttle down through the cell 21 toward the bobbin chute C to be described presently. In the particular arrangement set forth herein it is necessary of course that the second cell 21 be empty, or unoccupied by the shuttle, at the time of weft replenishment, but this condition is easily achieved by certain shuttle sequences and imposes no hardship upon the automatic operation of a loom of the type generally contemplated by my invention. My invention is not necessarily limited to use with the two cells 20 and 21 as shown in Figs. 1 and 2.

In carrying my invention into effect I provide a bobbin chute designated generally at C to be located below the cell 21 for the purpose of deflecting the outgoing bobbin D forwardly toward a bobbin can not shown. The bobbin chute comprises a floor 50 which is inclined upwardly and rearwardly and extends across the lowest cell 23 and into cell 22. The floor 50 is bent vertically as at 51 to lie along the shuttle box back 29 of cell 22. Bent up from the inner end of the floor 50 is a wing 53 which engages the head or butt 54 of the outgoing bobbin, while the outer or right end of the floor 50 as viewed in Fig. 1 has bent upwardly therefrom a second wing 55.

The floor 50 is mounted on two supporting feet, the right hand foot 60 extending behind the floor and being riveted thereto as at 61. Foot 60 is provided with a bearing 62 through which the binder pin 40 extends, and this bearing extends between the lowest lug 39 and the lug immediately thereabove. These two lugs effectively prevent objectionable vertical motion of the foot 60 and therefore of the right hand end of the bobbin chute as viewed in Fig. 1.

The left foot 65 is riveted as at 66 to the back of the floor 50 and as shown in Fig. 1 has two forward fingers 63 and one rear finger 64 spaced behind the front fingers a sufficient distance to receive the wall 35 of the gang of shuttle boxes. The fingers 63 project to the left sufficiently to extend between and engage the lowest pair of lugs 36 for the purpose of preventing objectionable vertical motion of the foot 65 and left end of floor 50 relatively to the gang of boxes. Thus it will be seen that both the right and left ends of the bobbin chute are held against vertical motion by engagement of the feet 60 and 65 with their corresponding lugs 39 and 36.

Assuming that the binders have been removed from the low cells 22 and 23 by raising pin 40, the tongues 63 and 64 will then be slid to the left along the wall 35 to assume some such position as shown in Figs. 1 and 6. This motion of the chute is made possible by the fact that the wing 55 is spaced from the lugs 39 a distance equal at least to the amount by which the tongues overlap the wall 35 and further because of the fact that the pin 40 is temporarily in raised position and the foot 60 can slide along the front face of the wall 38 to the left from the position shown in dotted lines in Fig. 6. When the chute has been moved to the left to its proper position the binder pin 40 will be lowered to pass through the bearing 62 and the chute will be held against horizontal motion with respect to the gang of boxes.

In order that the chute may not vibrate dur-

ing the back and forth motion of the lay, the wall 51 is so constructed that it is held by the resilience of the chute against the front surface of wall 29. When the pin 40 is passed through the bearing 62 it causes a slight twist in the chute the effect of which is to hold the wall 51 in close engagement with the wall 29 to prevent vibration.

When the chute is located as shown in Fig. 1 the inclined wing 53 is correctly positioned to engage the butt 54 of the outgoing bobbin D and the forward and downward inclination of the floor 50 directs the depleted bobbin forwardly. In passing downwardly the bobbin D will pass through the positions shown in dot and dash, and dotted lines, Fig. 1.

When the chute is to be removed for any purpose, the operations already described will be reversed, the pin 40 being raised to release the bearing 62 and the chute being then slid to the right to disengage the tongues 63 and 64 from the wall 35.

From the foregoing it will be seen that I have provided a simple form of bobbin chute which is held in position by the customary parts of a gang of shifting shuttle boxes, one end of the chute being positioned by means of a binder pin while the other end is positioned by the front wall 35 of the shuttle boxes. Furthermore, the lugs which are ordinarily provided for cooperation with the shuttle binders prevent objectionable vertical motion of the chute by engagement with the supporting feet 60 and 65. While I have shown a bearing 62 on one of the feet I do not wish necessarily to be limited to this construction. It will also be seen that the distance between the wing 55 and the lugs 39 is sufficient to permit the chute to be slid to the right as viewed in Fig. 1 a sufficient distance to disengage the tongues 63 and 64 from the front wall of the plate 35. Again, if desired, the inherent resilience of the material of which the chute is formed can be relied upon to hold the vertical top wall 51 against the back wall 29 of cell 22.

Having thus described my invention it will be seen that changes and modifications may be made therein by those skilled in the art without departing from the spirit and scope of the invention and I do not wish to be limited to the details herein disclosed, but what I claim is:

1. In a loom having a lay and a shuttle box on the lay to receive a shuttle which is held in position for a replenishing operation by a shuttle binder, a pin on the shuttle box to provide a pivotal support for the shuttle binder, a bobbin chute below the shuttle, means on one end of the chute to connect the pin and bobbin chute, and additional means on the other end of the chute to hold the latter to the shuttle box, said means and additional means holding the chute in the path of a depleted bobbin moving downwardly from the shuttle.

2. In a loom having a lay and a shuttle box on the lay to receive a shuttle which is held in position for a replenishing operation by a shuttle binder, a pivot pin on the shuttle box on which the shuttle binder is pivoted, and a bobbin chute having a part on one end thereof to engage the pivot pin and another part on the other end to hold the chute to the shuttle box, the latter and pin cooperating with said parts to hold the bobbin chute in the path of a bobbin moving downwardly from the shuttle.

3. In a multi-cell shuttle box for a weft replenishing loom, said shuttle box having a plurality of

vertically aligned cells in the upper of which is located a shuttle containing a depleted bobbin to be moved downwardly from the shuttle on a weft replenishing operation of the loom, a shuttle binder to hold the shuttle in position for replenishment on a weft replenishing operation, a binder pin on which the shuttle binder is pivoted, a bobbin chute under the shuttle extending into certain of the lower cells of the shuttle boxes and having a portion on one end to engage and be held by the binder pin and having a second portion at the other end held by the shuttle box, said portions cooperating with the pin and shuttle box to hold the chute in the path of a depleted bobbin moving downwardly from the shuttle.

4. In a multi-cell shuttle box for a weft replenishing loom, said shuttle box having a plurality of vertically aligned cells in the upper of which is located a shuttle containing a depleted bobbin to be moved downwardly from the shuttle on a weft replenishing operation of the loom, a shuttle binder to hold the shuttle in position for replenishment on a weft replenishing operation, a binder pin carried by the shuttle box on which the shuttle binder is pivoted, a bobbin chute having a downwardly and forwardly extending floor, means rigid with one end of the floor surrounding a portion of the pin, other means rigid with the other end of said floor held to the shuttle box, said means assisting in holding the floor of the chute in stationary position with respect to the shuttle box and in the path of a depleted bobbin moving downwardly from the shuttle.

5. In a loom having a lay with a shuttle box thereon having a cell to hold a shuttle from which a depleted bobbin is projected downwardly during a weft replenishing operation of the loom, a projection extending forwardly from the shuttle box, a bobbin chute below said cell, means on one end of the bobbin chute to engage said projection, said means and projection cooperating to prevent motion of the bobbin chute vertically with respect to the shuttle box and the shuttle in said cell and means to hold the other end of the chute fixed with respect to the shuttle box.

6. In a loom having a lay with a shuttle box thereon having a cell to hold a shuttle from which a depleted bobbin is projected downwardly during a weft replenishing operation of the loom, a pair of vertically spaced projections extending forwardly from the shuttle box, a bobbin chute below said cell, a foot on one end of said bobbin chute extending between and engaging said projections to prevent relative vertical motion of the bobbin chute with respect to the shuttle box and means to hold the other end of the chute fixed with respect to the shuttle box.

7. In a shuttle box for a weft replenishing loom, the shuttle box having a series of vertically aligned cells in the upper of which is located a shuttle held in position by a shuttle binder to receive a fresh carrier of weft simultaneously with the downward expulsion of a depleted carrier of weft from the shuttle during a weft replenishing operation of the loom, a lug projecting forwardly from the shuttle box, a binder pin extending through the lug to afford pivotal support for the shuttle binder, a bobbin chute having a downwardly and forwardly inclined floor located below the top cell, means on one end of the chute engaging the binder pin and the lug to cooperate with said pin and lug to assist in holding the bobbin chute in the path of a depleted carrier of weft descending from the shuttle and means

to hold the other end of the chute fixed with respect to the shuttle box.

8. In a shuttle box for a weft replenishing loom, the shuttle box having a series of vertically aligned cells in the upper of which is located a shuttle held in position by a shuttle binder to receive a fresh supply of weft simultaneously with the downward expulsion of a depleted supply of weft from the shuttle during a weft replenishing operation of the loom, a projection extending forwardly from the shuttle box, a binder pin extending through the projection and affording pivotal support for the shuttle binder, a bobbin chute having a forwardly and downwardly inclined floor located under the cell containing the shuttle to be replenished, means rigid with one end of the chute engaging the projection and having formed thereon a bearing which surrounds the binder pin, said projection resisting vertical motion of the adjacent end of the chute with respect to the shuttle box and the binder pin resisting forward motion of the chute with respect to the shuttle box and means to hold the other end of the chute fixed with respect to the shuttle box.

9. In a multi-cell shuttle box for a weft replenishing loom, said shuttle box having a top cell containing a shuttle from which a depleted weft carrier is expelled downwardly during the weft replenishing operation of the loom, a front wall forming part of the shuttle box, a bobbin chute having a forwardly and downwardly inclined floor under said top cell, means comprising horizontally spaced fingers rigid with the chute at one end thereof to engage opposite sides of the wall to prevent forward motion of the adjacent part of the chute relatively to the shuttle box and hold said part of the chute in the path of a weft carrier moving downwardly from the shuttle and means to hold the other end of the chute fixed with respect to the shuttle box.

10. In a multi-cell shuttle box construction for a weft replenishing loom, said shuttle box having the top cell to contain a shuttle to be replenished and have downwardly expelled therefrom a depleted weft carrier, a plurality of vertically spaced lugs projecting forwardly from the shuttle box, a front wall for the shuttle box supporting said lugs, a bobbin chute having a forwardly and downwardly inclined floor located under said top cell, means secured to the chute to engage the front and back surfaces of said wall to assist in resisting forward motion of the chute relatively to the shuttle box and also engaging said lugs to resist vertical motion of the adjacent part of the chute relatively to the shuttle box and means to hold the other end of the chute fixed with respect to the shuttle box.

11. In a bobbin chute for a shuttle box having a front wall adjacent to one end thereof extending below a shuttle receiving cell and having a shuttle binder pin adjacent to the other end thereof, said chute having a floor to be inclined downwardly and forwardly when the chute is in position under the shuttle receiving cell, a foot extending laterally from one end of the floor and having horizontally spaced fingers, one finger to be in front of and another finger to be behind the front wall, and a bearing for the binder pin extending laterally from the other end of the floor.

12. In a shuttle box having a top shuttle receiving cell from which a depleted weft carrier is expelled downwardly, said shuttle box having

vertical horizontally spaced front walls, a bobbin chute below the shuttle receiving cell having a downwardly and forwardly inclined floor, lateral wings extending upwardly from the floor on each side of the latter between said front walls, means on one side of the chute to establish a sliding and holding connection between one of the walls and said chute, said means having portions to engage opposite sides of said one front wall and project along the same a given distance, and means extending from the other side of the chute to have holding relation with part of the shuttle box, the distance between said wings plus said given distance being less than the distance measured horizontally between said front walls, whereby said floor and wings can be inserted between said walls and then slid horizontally to establish holding connection between the first said means and said one wall.

13. In a bobbin chute for a shuttle box having a shuttle receiving cell below which extend horizontally spaced vertical front walls from each of which a pair of vertically spaced projections extend forwardly, the shuttle box having a shuttle binder pin extending vertically through the projections of one of said walls, an inclined floor forming part of the chute, a bearing foot extending laterally from one end of the chute to receive the binder pin and extend between and engage the projections through which said binder pin extends, and a laterally extending foot on the other end of the floor to extend between and engage the projections of the other wall, said feet to prevent vertical motion of the chute relatively to the shuttle box by engagement with their respective pairs of projections.

WILLIAM A. BLANCHARD.
